UNITED STATES PATENT OFFICE.

KUROJI SATO, OF BERKELEY, CALIFORNIA.

HORN.

1,070,540.

Specification of Letters Patent. Patented Aug. 19, 1913.

Application filed July 17, 1912. Serial No. 709,995.

To all whom it may concern:

Be it known that I, KUROJI SATO, a subject of the Emperor of Japan, residing at Berkeley, in the county of Alameda and 5 State of California, have invented certain new and useful Improvements in Horns, of which the following is a specification.

My present invention relates to mechanical horns, and more particularly to such 10 apparatus used in connection with self propelled conveyances, such as automobiles, to give warning of their approach to an object.

The principal objects of my invention are to provide a horn which is mechanically 15 operated without the aid of wind, as in wind instruments; to enable the apparatus to produce a loud and distinct tone which will attract attention above the ordinary traffic noises, the duration of such tone being under control of the operator, and, by 20 the disposition and arrangement of parts, to provide means whereby the propelling mechanism of the conveyance may be utilized to actuate the sound producing element, thus avoiding the use of electric batteries, generators, or similar means, the efficiency of which is doubtful.

Other objects of my invention will appear 25 in the following detailed description in connection with the accompanying drawings, forming a part of this specification, which show a preferred form of apparatus embodying my invention.

In said drawings, Figure 1 is a fragmentary view of an automobile chassis showing 30 the application of my invention thereto. Fig. 2 is an enlarged side elevation of the apparatus, parts of the chassis supporting said apparatus being shown in connection therewith. Fig. 3 is a detailed view in 35 central vertical section through a portion of the bell member of the horn proper, parts being shown in side elevation. Fig. 4 is a cross sectional view on lines 4—4 of Fig. 3. Fig. 45 5 is a cross sectional view on the lines 5—5 of Fig. 2.

Similar characters refer to similar parts throughout the several views.

A suitable support, such as the longitudinal members of the chassis of an automobile 40 6, may support the apparatus, for practical purposes, it being desirable that the apparatus be mounted on structure rigid with the support of the operator. As a suitable means for operating the horn, as here-

inafter described, an engine 7 is employed, preferably the propelling mechanism of the automobile, the said engine being provided with a fly wheel 8.

The horn proper, designated generally by 45 9, comprises a bell portion 10; a casing 11 disposed at the smaller end of said bell portion; a member 12, preferably drum shaped, revoluble in said casing 11 and supported by a bearing 13, said member 12 being provided with a plurality of abutments 14, preferably in the form of lugs, and, a plurality of vibratable members 15, within casing 11 and disposed in the path of movement of abutments 14, to be vibrated upon rotation 50 of member 12. The members 15 are preferably metallic springs or plates, similar to those used in a music box, and which produce a tone of the desired pitch upon being vibrated. The abutments 14 may be arranged in any desired manner, either alined in rows longitudinally of the member 12, as shown in the drawing, or staggered.

The horn proper is preferably supported 55 by a base 16, formed integral with bearing 13 and mounted upon the frame member 6. I also prefer to carry revoluble member 12, upon a shaft 17, to which it is keyed, said shaft extending through bearing 13 and carrying one element 18 of a clutch device 60 85 designated generally by 19.

The mechanism for imparting movement to member 12 is designated generally by 20, and incorporates said clutch device 19 to transmit motion of the latter to the former 65 when such is desired. Mechanism 20 is suitably mounted upon a standard 21, carrying bearings 22 spaced apart from each other. Said bearings 22 carry a revoluble collar 23 to which is keyed a pulley 24 intermediate 70 said bearings, and whereby said sleeve is prevented from moving axially. The central opening 25 of collar 23 is such as to receive a movable stem 26, permitting axial movement of the stem, but compelling the 75 same to rotate with the collar when movement is imparted to the latter through pulley 24. To accomplish this, the said opening 25 may be square to receive a squared portion 27 of the stem 26, or any other 80 suitable keying means may be utilized.

Standard 21 may be mounted upon support 6 and disposed with the axis of stem 26 alined to the axis of shaft 17, of member 12, and said stem, at its end 110

nearest clutch member 18, carries a companion clutch member 28 of the clutch device 19. The clutch members 18 and 28 are normally drawn out of engagement with each other, by any suitable means, such as an expansion spring 29, abutting against the collar 23, encircling stem 26, and bearing against an abutment or pin 30 rigid with the latter. Suitable means for actuating said stem 26 to bring the clutch members into engagement, against action of spring 29, is designated generally at 31. This mechanism, as disclosed, may be of treadle type and comprises, a plunger 32 carried by a sleeve 33; a bell crank lever 34 carried by a bracket 35; the plunger 32 imparting movement to the lever by pin and slot engagement 36, with one arm thereof, the other arm having a pin 37 working in a circumferentially extending slot 38 formed in the stem 26. By depressing the plunger 32, the bell crank is actuated to move stem 26 axially against action of spring 29 to bring clutch members 18 and 28 into engagement. The sleeve 23, as disclosed, is adapted to receive rotation from a pulley 39 mounted concentric with fly wheel 8; a belt 40, connecting pulleys 39 and 24, as clearly shown in Fig. 1 of the drawing.

30 The operation of the device is as follows: Movement of the stem 26 may be imparted to the drum member 12, when clutch members 18 and 28 are brought into engagement. Such imparted movement of member 12, 35 causes the abutments 14, carried thereby, to vibrate members 15 causing a rapid series of tones which merge into one another so as to form a continuous sound, duration of which is controlled by the period of time the clutch members remain engaged. The sound issuing from bell member 10 has a clear and distinct tone.

Changes in detail may be made without departing from the spirit and scope of my 45 invention; but,

I claim:—

1. In a mechanical horn apparatus, the combination of a horn including a rotatable member and means vibratable upon movement of said member to produce a sound, a standard having two bearings spaced apart from each other, a collar having a polygonal central opening rotatable in the said bearings of said standard, a pulley keyed to said 50 collar and interposed between the said bearings of said standard, a stem having a portion in said opening in said collar constructed to be rotated therewith but axially movable with respect thereto, a clutch member 55 carried by said rotatable member of said horn, a companion clutch member carried by the said stem and facing said first mentioned clutch member, an expansion spring abutting against said collar at the face opposite 60 from said second mentioned clutch mem-

ber and encircling said stem, an abutment for the other end of said spring carried by the stem, and means for imparting axial movement of said stem against action of said spring, substantially as and for the 70 purpose set forth.

2. In a mechanical horn apparatus, the combination of a horn including a rotatable member and means vibratable upon movement of said member to produce a sound, a standard provided with bearings, a collar having a polygonal central opening, rotatable in the said bearings of said standard, but not axially movable with respect thereto, means for rotating said collar, a stem 75 having a portion in said opening in said collar constructed to be rotated therewith but axially movable with respect thereto, said stem being axially aligned with the said rotatable member of said horn, a clutch 80 member carried concentric with said rotatable member of said horn, a companion clutch member carried by said stem and facing said first mentioned clutch member, and mechanism for moving said stem in an axial 85 direction to clutch or unclutch said clutch members, substantially as and for the purpose set forth.

3. In a mechanical horn apparatus, the combination of a horn including a revolute member and means vibratable upon movement of said member to produce a sound, a standard provided with bearings, a collar, having a polygonal central opening, rotatable in the said bearings of said standard, but axially movable with respect thereto, means for rotating said collar, a stem 95 having a portion in said opening in said collar constructed to be rotated therewith, but axially movable with respect thereto, a 100 clutch member carried by said revolute member of said horn, a companion clutch member carried by said stem and facing said first mentioned clutch member, and mechanism for moving said stem in an axial direction to clutch or unclutch the clutch members, substantially as and for the purpose set forth.

4. In a mechanical horn apparatus, the combination of a horn including a revolute member and means vibratable upon movement of said member to produce a sound, a standard provided with bearings, a collar, having a polygonal central opening rotatable in the said bearings of said standard but axially movable with respect thereto, means for rotating said collar, a stem having a portion in said opening in said collar and constructed to be rotated therewith, but axially movable with respect thereto, a clutch member carried concentric with said revolute member of said horn, a companion clutch member carried by said stem, and facing said first mentioned clutch member, and mechanism for moving said 115 120 125 130

stem in an axial direction to clutch or unclutch said clutch members, substantially as and for the purpose set forth.

5. In a mechanical horn apparatus, the combination of a horn including a revolvable member and means vibratable upon movement of said member to produce a sound, a standard provided with bearings, a collar, having a polygonal central opening, rotatable in said bearings of said standard, but not axially movable with respect thereto, means for rotating said collar, a stem having a portion in said opening in said collar constructed to be rotated there-
10 with but axially movable with respect there-
15

to, a clutch member carried by said revolvable member of said horn, a companion clutch member carried by the stem and facing said first mentioned clutch member, and mechanism for moving said stem in an axial direction to clutch or unclutch said clutch members, substantially as and for the purpose set forth. 20

In testimony whereof I affix my signature in presence of two witnesses.

KUROJI SATO.
